US00D837330S

(12) **United States Design Patent** (10) **Patent No.:** **US D837,330 S**
(45) **Date of Patent:** **** Jan. 1, 2019**

(54) **ADAPTER MOUNT**

(71) Applicant: **Leapers, Inc.**, Livonia, MI (US)

(72) Inventors: **Tai-Lai Ding**, Northville, MI (US); **Tat Shing Yu**, Plymouth, MI (US)

(73) Assignee: **Leapers, Inc.**, Livonia, MI (US)

(**) Term: **15 Years**

(21) Appl. No.: **29/598,741**

(22) Filed: **Mar. 28, 2017**

(51) **LOC (11) Cl.** **22-01**

(52) **U.S. Cl.**

USPC **D22/108**

(58) **Field of Classification Search**

(57) **CLAIM**

The ornamental design for an adapter mount, as shown and described.

DESCRIPTION

FIG. 1 is a front/right side isometric view of the adapter mount of the present invention;

FIG. 2 is a front elevational view of the embodiment of FIG. 1;

FIG. 3 is a rear elevation view of the embodiment of FIG. 1;

FIG. 4 is a left side elevational view of the embodiment of FIG. 1;

FIG. 5 is a right side elevational view of the embodiment of FIG. 1;

FIG. 6 is a top view of the embodiment of FIG. 1; and,

FIG. 7 is a bottom view of the embodiment of FIG. 1.

The broken lines in the drawings are used to illustrate unclaimed portions of the invention and form no part of the claimed design.

1 Claim, 4 Drawing Sheets
